DU PONT RAYON COMPANY, OF NEW YORK, N. Y., A CORPORATION OF DELAWARE

RING SPINNING DEVICE FOR SPINNING CONTINUOUSLY-FED TEXTILE FIBERS

Application filed July 15, 1927, Serial No. 205,876, and in Great Britain July 29, 1926.

This invention relates to an improved ring spinning machine, capable of spinning any textile material, such as wool, cotton, linen, silk and artificial silk, provided, of course, in this last case, that the filaments to be spun have acquired a suitable consistency permitting them to undergo mechanical treatment so that they behave like any other textile material.

10 In the spinning of textile materials, difficulties exist in effecting in a practical way, capable of industrial use on a large scale, the fastening of the thread on the bobbin, which it is necessary to perform every time 15 the bobbin is changed. These difficulties occur when the filaments or threads to be spun by the ring spinning device are continuously fed to the spinning device. If this continuous feed be not interrupted when necessary 20 (when the bobbins are changed, for instance), a substantial length of filament will accumulate between the feed and the spinning device, and this is liable either to become entangled in the machinery or to become wound up on the feeding device, which 25 should, on the contrary, remain always perfectly clean for good working.

Moreover, even if the thread is kept under tension after passing through the feeding 30 device, the fastening of the thread on the bobbin cannot take place in the usual way by winding the thread once or twice round the bobbin. This operation either interrupts 35 the tension and the drawback mentioned occurs, or else the thread slides on the bobbin and, not being sufficiently secured thereto, it does not wind itself upon it at the moment when the bobbin is put in motion with the normal speed, and breakage occurs.

40 According to this invention, these difficulties are obviated by using, in combination with a receiving roller which, during the interruptions of the winding on the bobbin, receives the thread coming from the 45 feeding device in the known manner, a bobbin, the core of which is provided with one or more slits, preferably oblique, so disposed that the thread penetrates into one of these slits after passing through the ring, owing 50 to the up-and-down movement of the plate

carrying the ring, without becoming secured to the bobbin, this only taking place when the bobbin is started, neither earlier nor later, the thread suddenly becoming fastened to the core of the bobbin by the doubling of 55 the thread which takes place at the very moment when the bobbin begins to rotate.

In the drawings forming part of this specification Figure 1 is a front elevation of one modification of the apparatus comprising 60 this invention.

Figure 2 is a side view of the apparatus illustrated in Figure 1.

The following description will serve to further illustrate the nature of the invention, 65 but this is only intended as an example. The feeder may be of any known type, but in the description, the use of a set of fluted rollers *a* and *b*, such as are used in the hosiery industry, is illustrated. These fluted rollers 70 have their axes in the same horizontal plane, and are arranged so that the filament introduced by the small funnel *c* is ejected vertically downwards through another small funnel *d*, and is not liable to become wound 75 on either of those toothed wheels. The receiving roller *e* is placed directly below the point of issue of the thread from between the toothed wheels and in such a position that, in case of accidental breakage of the thread 80 during spinning, or while the bobbins are changed, the free extremity of the thread is taken up by this roller. This roller normally runs at a peripheral velocity equal to 85 the velocity of delivery, but it is capable of turning loosely on its shaft. The adjustment of the roller on the shaft is such that normally it is carried along by the shaft, but a minimum effort will be sufficient to cause 90 motion relative to the shaft. The bobbin *f* is provided with the fine oblique slit *g*, finished in such a way that there is no unevenness likely to chafe the thread wound on the bobbin, and that the thread is not secured to 95 the bobbin merely by the fact that it has entered the said slit. A ring *r* adapted to be rotated and reciprocated up and down in the usual manner is provided with rails *k*.

The operation of the apparatus will be 100

clearly understood from the following description thereof:

Assume that a bobbin has been doffed and an empty bobbin *f* has been mounted on the spindle *i*. During the doffing and mounting of the new bobbin *f* on the spindle *i* the thread fed by the rollers *a* and *b* is directed on to and received by the roller *e*. The course of the thread is illustrated in Figure 10 2 and designated by the reference numeral 1. After the bobbin has been mounted the operator manually moves the thread from position No. 1 to the position designated by the reference numeral 2. In the latter position 15 the thread passes through the guide *h* and through the rail *k* on the ring *r*. At this time the ring *r* does not revolve about the bobbin but merely reciprocates up and down. Accordingly, the rail *k* is motionless on the 20 ring *r*. During the reciprocation and especially in the upward movement thereof, the thread will engage the slot *g*. This is clearly illustrated in Figure 2, the reference character *r'* diagrammatically designating one 25 of the positions assumed by the ring *r* in its upward movement. When the thread is completely engaged in the slots, occupying the position designated by the reference numeral 2', the operator suddenly starts the 30 rotation of the spindle *i* and therefore the bobbin *f*. Substantially instantly and simultaneously with the beginning of the rotation of the bobbin, the thread is broken between the slot *g* and the roller *e* and securely 35 fastened to the bobbin. The rail begins to revolve and the winding is effected without any loss in tension of the thread fed by the feeding mechanism *a* and *b*. During the winding operation the thread assumes the 40 position designated by the reference numeral 3.

The complete operation of changing a bobbin can thus be very simply effected in from fifteen to twenty seconds, so that the length 45 of filament taken up by the receiving roller is insignificant in proportion to the entire length wound and spun on to a bobbin of normal dimensions.

What I claim and desire to secure by Letters Patent is:—

1. A process for the fastening of a continuously-fed textile thread on the bobbin of a ring spinning machine comprising traversing the thread on the motionless bobbin and causing it to engage a device on said bobbin whereby starting of the spindle bearing the bobbin secures an immediate fastening of the thread on said bobbin.

60 2. A process for the fastening of a continuously-fed textile thread on the bobbin of a ring spinning machine comprising traversing the thread on the motionless bobbin and causing it to enter a slit in the core of said 65 bobbin whereby starting of the spindle bear-

ing the bobbin secures an immediate fastening of the thread on said bobbin.

3. In a ring spinning machine for spinning continuously-fed textile threads a spindle, a bobbin mounted on said spindle, a reciprocating ring carrying a thread and causing it to traverse said bobbin, means on said bobbin to engage the thread traversing said bobbin, said means securely fastening the thread on said bobbin when the bobbin starts 75 rotating.

4. In a ring spinning machine for spinning continuously-fed textile threads a spindle, a bobbin mounted on said spindle, a reciprocating ring carrying a thread and causing it to traverse said bobbin, said bobbin having a slit in the core thereof adapted to engage the thread traversing said bobbin and to securely fasten the thread to said bobbin when the bobbin starts rotating.

85 5. In a ring spinning machine for spinning continuously-fed textile threads a spindle, a bobbin mounted on said spindle, a reciprocating ring carrying a thread and causing it to traverse said bobbin, said bobbin having 90 an oblique slit in the core thereof adapted to engage the thread traversing said bobbin and to securely fasten the thread to said bobbin when the bobbin starts rotating.

95 6. In a ring spinning machine for spinning continuously-fed textile threads, the combination of a spindle, a bobbin mounted on said spindle, means on said bobbin adapted to engage a thread traversing said bobbin and to fasten said thread on said bobbin when 100 said bobbin starts rotating, and a roller to receive the continuously-fed thread when the bobbin is being removed and prior to the fastening of the thread on another bobbin.

105 7. In a ring spinning machine for spinning continuously-fed textile threads, the combination of a spindle, a bobbin mounted on said spindle, said bobbin having a slit in the core thereof adapted to engage a thread 110 traversing said bobbin and to securely fasten the thread to said bobbin when said bobbin starts rotating and a roller to receive the continuously-fed thread when the bobbin is being removed and prior to the fastening of said thread on another bobbin.

115 In testimony whereof I have signed my name to this specification.

HENRI FRANCOIS NIOGRET.
